UNITED STATES PATENT OFFICE

CHARLES J. ROSS, OF OAKLAND, CALIFORNIA

DESIGN FOR A SAFE FOR DISCARDED RAZOR BLADES

Application filed February 25, 1930. Serial No. 34,647. Term of patent 3½ years.

To all whom it may concern:

Be it known that I, CHARLES J. Ross, a citizen of the United States, and a resident of Oakland, in the county of Alameda and State of California, have invented a new, original, and ornamental Design for Safe for Discarded Razor Blades, of which the following is a specification, reference being had to the accompanying drawing, forming part thereof.

I claim:

The ornamental design for a safe for discarded razor blades, substantially as shown.

CHARLES J. ROSS.
